UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

MINING MACHINE.

Application filed August 31, 1925. Serial No. 53,726.

This invention relates to mining machines and more particularly to mining machines of the continuous cutter type adapted to be fed laterally relative to the face of the coal to cut a substantially horizontal kerf thereunder.

The primary object of this invention is to provide an improved mining machine having improved feeding means therefor whereby the machine may be moved about the mine at a fast speed, dumped into the coal at a slower or intermediate speed, and fed laterally relative to the face of the coal at a slow or cutting speed. Still another object of my invention is to provide improved means for a mining machine of extremely compact structure whereby three distinct feeding speeds may be obtained. These and other objects of my invention will, however, subsequently more fully appear.

A preferred embodiment of this invention may comprise a main frame slidable on its bottom on the mine bottom and having mounted thereon a rigid forwardly projecting cutter chain carrying cutter bar. The machine may be propelled both during cutting and at other times preferably by one or more of a pair of flexible feeding members secured at their free ends at the advancing and receding sides of the machine, respectively, and with which a plurality of rotatable feed operating members cooperate in effecting feeding and controlling movement of the machine. A single motor preferably supplies power both to the cutting and feeding mechanisms and is mounted on the main frame at the forward end of the latter in a position overlying the rear end of the cutter bar. Power may be transmitted from the motor to the cutting and feeding mechanisms by means including a motor pinion on the rear end of the armature shaft and improved variable speed transmission mechanism. Preferably the transmission mechanism comprises a plurality of coaxial differential mechanism disposed on a transverse axis and having driving and controlling elements associated therewith. This improved transmission mechanism may effect winding in of the flexible feeding members at a plurality of different speeds.

In the accompanying drawings I have shown for purposes of illustration one form which my invention may assume in practice.

In these drawings,—

Fig. 1 is a plan view of a mining machine constructed in accordance with one embodiment of my invention, a portion of the cutting and feed transmission mechanism being shown in section to facilitate illustration. 60

Fig. 2 is a partial side elevational view of the machine shown in Fig. 1, a portion of the cutting and feed transmission mechanism being shown in central longitudinal vertical section. 65

Fig. 3 is a detail sectional view taken substantially on line 3—3 of Fig. 1.

Fig. 4 is a detail sectional view taken substantially on line 4—4 of Fig. 3.

Referring to the drawings, 1 designates generally a mining machine of the continuous cutter flexibly fed room and pillar type having a machine frame 2 slidable on its bottom 3 on the mine bottom. The frame 2 comprises a bed section 4, a motor section 5, and a feed and cutting mechanism carrying section 6, the sections 5 and 6 being mounted upon the bed section 4 and rigidly secured to the latter in any approved manner. Rigidly secured within the bed section 4 and projecting forwardly from the machine frame is a cutter bar 7 about the outer edge of which a cutter bit carrying cutter chain 8 is adapted to be circulated. As shown, the motor section 5 is carried at the forward end of the machine frame, and overlies the rear end of the cutter bar 7. As illustrated, housed within the motor section 5 is a motor 9, herein preferably of the reversible electric type, having a longitudinally extending horizontal armature shaft 10. Secured, as by a spline and screw connection 11, to the rear end of the armature shaft 10 is a spur motor pinion 12 having its reduced hub portion journaled within ball bearings 13 suitably carried within the machine frame 2. 85 90 95

In specifically describing the improved cutter chain actuating mechanism it will be noted that meshed with the motor pinion 12 is a spur gear 13 rigidly secured to a horizontal longitudinally extending shaft 14 disposed below and extending rearwardly away from the armature shaft 10. The shaft 14 is journaled within ball bearings 15 carried within a bracket 16 suitably secured to the machine frame. Carried on the rear end of the shaft 14 is a bevel pinion 17 which meshes with a large bevel gear 18 splined as at 19 to a vertically disposed shaft 20 jour- 100 105 110

naled as at 21 within the bed section 4. Suitably secured to the lower end of the shaft 20 is a spur pinion 22 which meshes with a large spur gear 23 secured in any approved manner to a sprocket 24 which rotates on a vertical axis and which cooperates to drive the cutter chain 8 in a usual manner. Suitable clutch mechanism, not shown, of any well known form is provided between the gear 23 and the sprocket 24.

In specifically describing the improved feeding mechanism it will be observed that disposed coaxially with the shaft 20 and splined as at 25 to the bevel gear 18 is a shaft 26 journaled at its upper end in ball bearings 27 suitably carried by the machine frame 2. Furthermore, splined to the lower end of the shaft 26 is a spur gear 28 which meshes at opposite sides thereof with spur gears 29 and 30 to drive the same in opposite directions. The gears 29 and 30 are suitably rigidly secured to the lower ends of shafts 31 and 32, respectively, and these shafts are suitably journaled in bearings 33 and 34 carried by the machine frame 2. As illustrated, rigid with and at the upper end of the shaft 31 is a spur gear 35 which drives, through an intermediate gear 36, a spur 37 loosely journaled on the shaft 26 above the gear 28. Furthermore, loosely journaled on the shaft 26 intermediate its ends is a worm 38 held in position by radially expansible split rings 38^a while splined to the shafts 31 and 32, respectively, are worms 39 and 40. As illustrated, the worm 38 is adapted to be selectively driven at different speeds in opposite directions from the gears 28 and 37, respectively, by means of clutch mechanism including clutch members 40^a and 41 splined to the hubs of the gears 28 and 37, respectively, and these clutch members are provided with clutch teeth 42 and 43, respectively, adapted to cooperate with clutch teeth 44 and 45 formed on the opposite ends of the worm 38. Clutch shippers 46 and 46^a are provided for the clutch members 40^a and 41 respectively and these shipper members are connected together by means of a pivotally connected link 47. As shown, the shipper member 46 is journaled on a transversely disposed shaft 48 suitably journaled within bearings 49 carried by the machine frame 2 while the clutch member 46^a is secured to a transversely disposed horizontal actuating shaft 50 journaled at 51 at its opposite ends on the sides of the machine frame. Secured to the end of the shaft 50 at the advancing side of the machine is an operating lever 52. From the foregoing description it will be evident that when the operator suitably manipulates the lever 52 one or the other of the gears 28 and 37 may be connected in operative driving relation with the worm 38. It is obvious that the ratio of the teeth on the gears 35

and 37 and the inclination of the teeth on the worms 38, 39 and 40 may be varied, thereby obtaining different feeding speeds to suit different conditions. Meshing with the worm 38 is a worm gear 53 disposed on a transverse horizontal axis and having oppositely projecting hub portions 54 journaled within suitable ball bearings 55 mounted within brackets 56 carried by the machine frame 2. As shown, the hub of the worm gear 53 is splined as at 57 to the adjacent hubs of bevel gears 58 and 59. Furthermore, the worms 39 and 40 are meshed with worm gears 60 and 61, respectively, arranged coaxially with the worm gear 53 and the hubs of these gears 60 and 61 are splined at 62 to the hubs of bevel gears 63 and 64, respectively, similar to the gears 58 and 59. Meshing with the gears 58, 63 and 59, 64, respectively, are planetary bevel pinions 65 and 66 journaled on radially projecting stub shafts 67 supported by planet carrier members 68 and 69. The hubs of these carrier members are splined at 70 to coaxially disposed shafts 71, 72, respectively, the latter having their inner ends journaled within a bearing sleeve 73 carried within the hubs of the bevel gears 58 and 59 while their outer ends are journaled within sleeves 73^a which rotate in ball bearings 74 supported by a detachable cover plate 75 forming a portion of the machine frame 2. It will herein be observed that splined at 76 to each of the shafts 71 and 72 is a clutch member 77 which carries a series of clutch disks 78. The disks 78 are interleaved with a series of clutch disks 79 carried by a clutch housing member 80 carried by the sleeves 73^a and also journaled on a bearing sleeve 81 carried by the hub of the member 77. As shown, journaled upon a bearing sleeve 82 carried by each of the shafts 71, 72 is a clutch disk retaining and housing member 83 having a hub portion on which a clutch applying member 84 is slidably mounted, the latter having projecting fingers 84^a which extend through apertures formed in the retaining member 83 into engagement with certain of the series of clutch disks 78, 79. Cooperating with the member 84 is a shipper member 85 secured to a vertically disposed actuating shaft 86 journaled within the machine frame. Suitably secured to the upper end of the shaft 86 is an operating lever 87. As illustrated, splined at 88 to the sleeves of the housing members 80 are drums 89 and 90 suitably journaled upon the side plates 75. Cooperating with the drums 89 and 90, respectively, are flexible feeding members 91 and 92 herein in the form of wire ropes or cables. Moreover it will be observed that carried by the opposite sides of the forward end of the machine frame 2 are guide sheaves 93 while suitably arranged on a projecting ledge 94

formed on the frame section 6 are a plurality of guide sheaves 93 and these sheaves 93 and 95 are adapted to guide the feed cables during the various operations of the machine.

It will be evident that when the operator suitably manipulates the levers 87, the drums 89 and 90 may be connected in operative driving relation with the shaft 71, 72 or may remain idle at will. It will also be evident that when the worms 38, 39, and 40 are simultaneously rotated in the same direction, one feeding speed is obtained; while if the worms 39 and 40 are rotated and the worm 38 held stationary another feeding speed is obtained and if the worm 38 is rotated in an opposite direction from the worms 39 and 40 a third feeding speed is obtained, the rotation of the bevel gears 58, 59 when driven by the worm 38 in opposite directions adding to or subtracting from the speed of rotation of the planet carriers 68 and 69. It will be understood that the speeds obtainable may be widely varied by suitable alterations in driving gearing and worm inclinations, and the angular speeds of the feed operating members will be equal to one-half the speed of their respective bevel gears 63 or 64, plus or minus one-half the speed of their respective bevel gears 58 or 59, it being of course evident that the latter speed may be equal to zero when the gears 58 and 59 are stationary and that the plus is used when the bevels 58 and 59 rotate in the same direction as their respective gears 63 and 64.

In the operation of my improved mining machine, it will be noted that when the machine has been transported to the room on its transport truck and unloaded therefrom, one or the other of the cables 91, 92 may be extended to a point adjacent the right hand rib of the coal and anchored by a suitable roof jack or take up device. The clutch teeth 42 of the clutch member 40* are then connected to the clutch teeth 44 formed on the worm 38; rotating the latter at its fast speed in an opposite direction from the rotation of the worms 39 and 40, and consequently the worm gears 53, 60 and 61 and the bevel gears 58, 59, 63, and 64 are rotated together at their respective speeds in the same direction, causing the planetary carriers to be rotated with the bevel gears and rotating the shafts 71, 72 at a relatively high speed. The desired feed drum 89, 90 is then connected in operative driving relation with the driving shaft by means of the clutches 78, 79 and the desired cable wound in and the machine fed toward the right hand rib at a fast or moving speed. When the cutter bar assumes an appropriate position adjacent the face of the coal the feed cable 91 is extended forwardly around the guide sheave 93 at the advancing side of the machine and then laterally to the left hand rib

of the coal, the free end of the cable being anchored in position by a suitable roof jack or a take up device. The clutch members 40* and 41 are then thrown into their neutral position, it being understood that the worm 38 is self-locking with the worm gear 53; thus preventing rotation of the worm gear and the bevel gears 58 and 59 at that time. As the worms 39 and 40 are constantly driven, the worm gears 60 and 61 and the bevel gears 63 and 64 are rotated, thus causing the planetary pinions 65 and 66 to react on the stationary bevel gears 58 and 59, respectively, consequently causing the planetary carriers 68, 69 to drive the shafts 71 and 72 at an intermediate speed. The friction clutch controlling the drum 90 is then applied and the machine dumped into the coal, the friction clutch controlling the drum 89 maintaining a desired controlling tension on the cable 91 at that time. The clutch teeth 43 are then thrown into engagement with the clutch teeth 45 formed on the worm 38 causing the latter to be rotated at a slower speed and in the same direction as the rotation of the worms 39 and 40. The bevel gears 58 and 59 are then rotated in the opposite direction from the rotation of the bevel gears 63 and 64, thus subtracting from the speed of the planet carriers 68, causing the shafts 71, 72 to be driven at a slow speed. The clutch 78, 79 controlling the drum 89 is then connected, causing the latter to wind in the cable 91 at a slow or cutting speed and the machine is straightened up and fed laterally across the face, the drum 90 acting on the receding cable 92 maintaining a desired controlling tension thereon, thus preventing the bar from being swung outwardly from the kerf. It will herein also be noted that by suitable operation of the clutches 78, 79 controlling the drums 89 and 90 the angle of the machine relative to the face of the coal may be controlled at will. Other operations of my improved mining machine will be clearly apparent to those skilled in the art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, a motor, and feeding mechanism driven by said motor including coaxial elements rotating on transversely extending horizontal axes, planet means cooperating with said elements, and vertical worms operatively connected to said coaxial elements respectively.

2. In a mining machine, a motor, and feeding mechanism driven by said motor including coaxial elements rotating on transversely extending horizontal axes, planet means co-operating with said elements, and vertical worms rotating on axes lying in the same transversely extending plane operatively connected to said coaxial elements respectively.
- 10 3. In a mining machine, a motor, and feeding mechanism driven by said motor including coaxial elements rotating on transversely extending horizontal axes, planet means co-operating with said elements, vertical worms operatively connected to said coaxial elements, and means for rotating one of said worms in opposite directions.
- 15 4. In a mining machine, a motor, and feeding mechanism driven by said motor including coaxial elements rotating on transversely extending horizontal axes, planet means co-operating with said elements, vertical worms operatively connected to said coaxial elements, and means for rotating one of said worms in opposite directions at different speeds.
- 20 5. In a mining machine, a motor, and feeding mechanism driven by said motor including coaxial elements rotating on transversely extending horizontal axes, planet means co-operating with said elements, vertical worms operatively connected to said coaxial elements, and means for rotating one of said worms in opposite directions at different speeds.
- 25 6. In a mining machine, a motor, and feeding mechanism driven by said motor including coaxial elements rotating on transversely extending horizontal axes, planet means co-operating with said elements, vertical worms operatively connected to said coaxial elements, and means for rotating one of said worms continuously and the other at will.
- 30 7. In a mining machine, a motor, and feeding mechanism driven by said motor including coaxial elements rotating on transversely extending horizontal axes, planet means co-operating with said elements, vertical worms operatively connected to said coaxial elements, and means for rotating one of said worms continuously and the other at will in either direction.
- 35 8. In a mining machine, a motor, and feeding mechanism driven by said motor including like coaxial elements rotating on transversely extending horizontal axes, planet means co-operating with said elements, and vertical worms rotating on axes lying in the same transversely extending plane operatively connected to said coaxial elements respectively.
- 40 9. In a mining machine, a motor, and feeding mechanism driven by said motor including like coaxial elements rotating on transversely extending horizontal axes, planet means co-operating with said elements, and vertical worms operatively connected to said coaxial elements, and means for rotating one of said worms in opposite directions.
- 45 10. In a mining machine, a motor, and feeding mechanism driven by said motor including like coaxial elements rotating on transversely extending horizontal axes, planet means co-operating with said elements, vertical worms operatively connected to said coaxial elements, and means for rotating one of said worms in opposite directions at different speeds.
- 50 11. In a mining machine, a motor, and feeding mechanism driven by said motor including like coaxial elements rotating on transversely extending horizontal axes, planet means co-operating with said elements, vertical worms operatively connected to said coaxial elements, and means for rotating one of said worms continuously and the other at will.
- 55 12. In a mining machine, a motor, and feeding mechanism driven by said motor including like coaxial elements rotating on transversely extending horizontal axes, planet means co-operating with said elements, vertical worms operatively connected to said coaxial elements, and means for rotating one of said worms continuously and the other at will in either direction.
- 60 13. In a mining machine, feeding mechanism including a plurality of pairs of coaxial elements rotating on horizontal transversely extending axes, planet means co-operating with the elements of each pair, and means for rotating said coaxial elements including worms rotating on vertical axes, one of said worms driving an element of each pair.
- 65 14. In a mining machine, feeding mechanism including a plurality of pairs of coaxial elements rotating on horizontal transversely extending axes, planet means co-operating with the elements of each pair, and means for rotating said coaxial elements including worms rotating on vertical axes lying in the same transverse plane, one of said worms driving an element of each pair.
- 70 15. In a mining machine, feeding mechanism including a plurality of pairs of coaxial elements rotating on horizontal transversely extending axes, planet means co-operating with the elements of each pair, and means for rotating said coaxial elements including three worms rotating on vertical axes, the central worm driving an element of each pair, and means for effecting rotation of said worms including means for rotating said last mentioned worm in opposite directions.
- 75 16. In a mining machine, feeding mechanisms including a plurality of pairs of coaxial elements rotating on horizontal transversely extending axes, planet means co-operating with the elements of each pair,

and means for rotating said coaxial elements including three worms rotating on vertical axes, the central worm driving an element of each pair, and means for effecting rotation of said worms including means for rotating said last-mentioned worm at different speeds.

of each pair, and means for effecting rotation of said worms including means for rotating said last-mentioned worm in opposite directions and said other worms continuously in the same direction.

70

17. In a mining machine, feeding mechanism including a plurality of pairs of coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds in opposite directions.

22. In a mining machine, feeding mechanism including a plurality of pairs of coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds and said other worms continuously in the same direction. 75 80

20 18. In a mining machine, feeding mechanism including a plurality of pairs of coaxial elements rotating on horizontal transversely extending axes, planet means cooperating with the elements of each pair, and
25 means for rotating said coaxial elements including three worms rotating on vertical axes, the central worm driving an element of each pair, and means for effecting rotation of said worms including means for rotating said last mentioned worm in opposite directions or allowing it to remain stationary.

23. In a mining machine, feeding mechanism including a plurality of pairs of coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds in opposite directions and said other worms continuously in the same direction.

19. In a mining machine, feeding mechanism including a plurality of pairs of coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds or allowing it to remain stationary.

24. In a mining machine, feeding mechanism including a plurality of pairs of coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm in opposite directions or allowing it to remain stationary and said other worms continuously in the same direction. 100 105 110

45 20. In a mining machine, feeding mechanism including a plurality of pairs of coaxial elements rotating on horizontal transversely extending axes, planet means cooperating with the elements of each pair, and means
50 for rotating said coaxial elements including three worms rotating on vertical axes, the central worm driving an element of each pair, and means for effecting rotation of said worms including means for rotating said last mentioned worm at different speeds in opposite directions or allowing it to remain stationary.

25. In a mining machine, feeding mechanism including a plurality of pairs of coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds or allowing it to remain stationary and said other worms continuously in the same direction. 115 120 125

60 21. In a mining machine, feeding mechanism including a plurality of pairs of coaxial elements rotating on horizontal transversely extending axes, planet means cooperating with the elements of each pair, and means for rotating said coaxial elements including three worms rotating on vertical axes, the central worm driving an element

26. In a mining machine, feeding mechanism including a plurality of pairs of coaxial elements rotating on horizontal transversely extending axes, planet means cooperating with the elements of each pair, and

means for rotating said coaxial elements including three worms rotating on vertical axes, the central worm driving an element of each pair, and means for effecting rotation of said worms including means for rotating said last mentioned worm at different speeds in opposite directions or allowing it to remain stationary and said other worms continuously in the same direction.

10 27. In a mining machine, feeding mechanism including a plurality of pairs of like coaxial elements rotating on horizontal transversely extending axes, planet means cooperating with the elements of each pair, and means for rotating said coaxial elements including worms rotating on vertical axes, one of said worms driving an element of each pair.

20 28. In a mining machine, feeding mechanism including a plurality of pairs of like coaxial elements rotating on horizontal transversely extending axes, planet means cooperating with the elements of each pair, and means for rotating said coaxial elements including worms rotating on vertical axes lying in the same transverse plane, one of said worms driving an element of each pair.

30 29. In a mining machine, feeding mechanism including a plurality of pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm in opposite directions.

40 30. In a mining machine, feeding mechanism including a plurality of pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds.

50 31. In a mining machine, feeding mechanism including a plurality of pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds in opposite directions.

60 32. In a mining machine, feeding mecha-

nism including a plurality of pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm in opposite directions or allowing it to remain stationary.

70 33. In a mining machine, feeding mechanism including a plurality of pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds or allowing it to remain stationary.

80 34. In a mining machine, feeding mechanism including a plurality of pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds in opposite directions or allowing it to remain stationary.

90 35. In a mining machine, feeding mechanism including a plurality of pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm in opposite directions and said other worms continuously in the same direction.

100 36. In a mining machine, feeding mechanism including a plurality of pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds and said other worms continuously in the same direction.

40. In a mining machine, feeding mechanism including a plurality of pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds in opposite directions.

45. In a mining machine, feeding mechanism including a plurality of coaxial pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds in opposite directions or allowing it to remain stationary and said other worms continuously in the same direction.

50. In a mining machine, feeding mechanism including a plurality of coaxial pairs of like coaxial elements rotating on horizontal transversely extending axes, planet means cooperating with the elements of each pair, and means for effecting rotation of said worms including means for rotating said last mentioned worm at different speeds in opposite directions.

41. In a mining machine, feeding mechanism including a plurality of coaxial pairs of like coaxial elements rotating on horizontal transversely extending axes, planet means cooperating with the elements of each pair, and means for rotating said coaxial elements including worms rotating on vertical axes, one of said worms driving an element of each pair.

42. In a mining machine, feeding mechanism including a plurality of coaxial pairs of like coaxial elements rotating on horizontal transversely extending axes, planet means cooperating with the elements of each pair, and means for rotating said coaxial elements including worms rotating on vertical axes, one of said worms driving an element of each pair, and means for rotating said last mentioned worm in opposite directions or allowing it to remain stationary.

43. In a mining machine, feeding mechanism including a plurality of coaxial pairs of like coaxial elements rotating on horizontal transversely extending axes, planet means cooperating with the elements of each pair, and means for rotating said coaxial elements including worms rotating on vertical axes, one of said worms driving an element of each pair, and means for rotating said last mentioned worm in opposite directions or allowing it to remain stationary.

42. In a mining machine, feeding mechanism including a plurality of coaxial pairs of like coaxial elements rotating on horizontal transversely extending axes, planet elements including three worms rotating on vertical axes, the central worm driving an element of each pair, and means for effecting rotation of said worms including means

for rotating said last mentioned worm at different speeds or allowing it to remain stationary.

48. In a mining machine, feeding mechanism including a plurality of coaxial pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds in opposite directions or allowing it to remain stationary.

49. In a mining machine, feeding mechanism including a plurality of coaxial pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm in opposite directions and said other worms continuously in the same direction.

50. In a mining machine, feeding mechanism including a plurality of coaxial pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds and said other worms continuously in the same direction.

51. In a mining machine, feeding mechanism including a plurality of coaxial pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds in opposite directions and said other worms continuously in the same direction.

52. In a mining machine, feeding mechanism including a plurality of coaxial pairs of like coaxial elements rotating on horizontal transversely extending axes, planet means cooperating with the elements of each pair, and means for rotating said coaxial elements including three worms rotating on vertical axes, the central worm driving an element of each pair, and means for effect-

ing rotation of said worms including means for rotating said last mentioned worm in opposite directions or allowing it to remain stationary and said other worms continuously in the same direction.

53. In a mining machine, feeding mechanism including a plurality of coaxial pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds or allowing it to remain stationary and said other worms continuously in the same direction.

54. In a mining machine, feeding mechanism including a plurality of coaxial pairs of like coaxial elements rotating on horizontal transversely extending axes, planet means cooperating with the elements of each pair, and means for rotating said coaxial elements including three worms rotating on vertical axes, the central worm driving an element of each pair, and means for effecting rotation of said worms including means for rotating said last mentioned worm at different speeds in opposite directions or allowing it to remain stationary and said other worms continuously in the same direction.

55. In a mining machine, feeding mechanism including a plurality of coaxial pairs of like coaxial elements rotating on horizontal transversely extending axes, planet means cooperating with the elements of each pair, means for rotating said coaxial elements including worms rotating on vertical axes, one of said worms driving an element of each pair, and feed operating members coaxial with said coaxial elements.

56. In a mining machine, feeding mechanism including a plurality of coaxial pairs of like coaxial elements rotating on horizontal transversely extending axes, planet means cooperating with the elements of each pair, means for rotating said coaxial elements including worms rotating on vertical axes lying in the same transverse plane, one of said worms driving an element of each pair, and feed operating members coaxial with said coaxial elements.

57. In a mining machine, feeding mechanism including a plurality of coaxial pairs of like coaxial elements rotating on horizontal transversely extending axes, planet means cooperating with the elements of each pair, and means for rotating said coaxial elements including three worms rotating on vertical axes, the central worm driving an element of each pair, means for effecting rotation of said worms including means for

rotating said last mentioned worm in opposite directions, and feed operating members coaxial with said coaxial elements.

58. In a mining machine, feeding mechanism including a plurality of coaxial pairs of like coaxial elements rotating on horizontal transversely extending axes, planet means cooperating with the elements of each pair, and means for rotating said coaxial 5 elements including three worms rotating on vertical axes, the central worm driving an element of each pair, means for effecting rotation of said worms including means for rotating said last mentioned worm at different 10 speeds, and feed operating members coaxial with said coaxial elements.

59. In a mining machine, feeding mechanism including a plurality of coaxial pairs of like coaxial elements rotating on horizontal transversely extending axes, planet means cooperating with the elements of each pair, and means for rotating said coaxial 20 elements including three worms rotating on vertical axes, the central worm driving an element of each pair, means for effecting rotation of said worms including means for rotating said last mentioned worm at different 25 speeds in opposite directions, and feed operating members coaxial with said coaxial 30 elements.

60. In a mining machine, feeding mechanism including a plurality of coaxial pairs of like coaxial elements rotating on horizontal transversely extending axes, planet 35 means cooperating with the elements of each pair, and means for rotating said coaxial elements including three worms rotating on vertical axes, the central worm driving an element of each pair, and means for effecting rotation of said worms including means for rotating said last mentioned worm in opposite directions or allowing it to remain 40 stationary, and feed operating members coaxial with said coaxial elements.

61. In a mining machine, feeding mechanism including a plurality of coaxial pairs of like coaxial elements rotating on horizontal transversely extending axes, planet means 45 cooperating with the elements of each pair, and means for rotating said coaxial elements including three worms rotating on vertical axes, the central worm driving an element of each pair, means for effecting rotation of said worms including means for rotating said last mentioned worm at different speeds or allowing it to remain stationary, and feed operating members coaxial with said coaxial 55 elements.

62. In a mining machine, feeding mechanism including a plurality of coaxial pairs of like coaxial elements rotating on horizontal transversely extending axes, planet means 60 cooperating with the elements of each pair, and means for rotating said coaxial elements

including three worms rotating on vertical axes, the central worm driving an element of each pair, means for effecting rotation of said worms including means for rotating said last mentioned worm at different speeds in opposite directions or allowing it to remain stationary, and feed operating members coaxial with said coaxial elements.

63. In a mining machine, feeding mechanism including a plurality of coaxial pairs of like coaxial elements rotating on horizontal transversely extending axes, planet means 70 cooperating with the elements of each pair, and means for rotating said coaxial elements including three worms rotating on vertical axes, the central worm driving an element of each pair, means for effecting rotation of said worms including means for rotating said last mentioned worm in opposite directions and said other worms continuously in the same direction, and feed operating members coaxial with said coaxial elements.

64. In a mining machine, feeding mechanism including a plurality of coaxial pairs of like coaxial elements rotating on horizontal transversely extending axes, planet means 75 cooperating with the elements of each pair, and means for rotating said coaxial elements including three worms rotating on vertical axes, the central worm driving an element of each pair, means for effecting rotation of said worms including means for rotating said last mentioned worm at different speeds and said other worms continuously in the same direction, and feed operating members coaxial with said coaxial elements.

65. In a mining machine, feeding mechanism including a plurality of coaxial pairs of like coaxial elements rotating on horizontal transversely extending axes, planet means 80 cooperating with the elements of each pair, and means for rotating said coaxial elements including three worms rotating on vertical axes, the central worm driving an element of each pair, means for effecting rotation of said worms including means for rotating said last mentioned worm at different speeds in opposite directions and said other worms continuously in the same direction, and feed operating members coaxial with said coaxial elements.

66. In a mining machine, feeding mechanism including a plurality of coaxial pairs of like coaxial elements rotating on horizontal transversely extending axes, planet means 85 cooperating with the elements of each pair, and means for rotating said coaxial elements including three worms rotating on vertical axes, the central worm driving an element of each pair, means for effecting rotation of said worms including means for rotating said last mentioned worm in opposite directions or allowing it to remain stationary and

said other worms continuously in the same direction, and feed operating members coaxial with said coaxial elements.

67. In a mining machine, feeding mechanism including a plurality of coaxial pairs of like coaxial elements rotating on horizontal transversely extending axes, planet means cooperating with the elements of each pair, and means for rotating said coaxial elements 10 including three worms rotating on vertical axes, the central worm driving an element of each pair, means for effecting rotation of said worms including means for rotating said last mentioned worm at different speeds 15 or allowing it to remain stationary and said other worms continuously in the same direction, and feed operating members coaxial with said coaxial elements.

68. In a mining machine, feeding mechanism 20 including a plurality of coaxial pairs of like coaxial elements rotating on horizontal transversely extending axes, planet means cooperating with the elements of each pair, and means for rotating said coaxial elements 25 including three worms rotating on vertical axes, the central worm driving an element of each pair, means for effecting rotation of said worms including means for rotating said last mentioned worm at different speeds 30 in opposite directions or allowing it to remain stationary and said other worms continuously in the same direction, and feed operating members coaxial with said coaxial elements.

69. In a mining machine, feeding mechanism including a plurality of coaxial pairs of like coaxial elements rotating on horizontal transversely extending axes, planet means 40 cooperating with the elements of each pair, means for rotating said coaxial elements including worms rotating on vertical axes, one of said worms driving an element of each pair, feed operating members coaxial with said coaxial elements, and clutch means coaxial 45 therewith.

70. In a mining machine, feeding mechanism including a plurality of coaxial pairs of like coaxial elements rotating on horizontal transversely extending axes, planet means 50 cooperating with the elements of each pair, means for rotating said coaxial elements including worms rotating on vertical axes lying in the same transverse plane, one of said worms driving an element of each pair, feed 55 operating members coaxial with said coaxial elements, and clutch means coaxial therewith.

71. In a mining machine, feeding mechanism including a plurality of coaxial pairs 60 of like coaxial elements rotating on horizontal transversely extending axes, planet means cooperating with the elements of each pair, and means for rotating said coaxial elements including three worms rotating on vertical axes, the central worm driving an element 65

of each pair, means for effecting rotation of said worms including means for rotating said last mentioned worm in opposite directions, feed operating members coaxial with said coaxial elements, and clutch means coaxial therewith. 70

72. In a mining machine, feeding mechanism including a plurality of coaxial pairs of like coaxial elements rotating on horizontal transversely extending axes, planet 75 means cooperating with the elements of each pair, and means for rotating said coaxial elements including three worms rotating on vertical axes, the central worm driving an element of each pair, means for effecting rotation of said worms including means for rotating said last mentioned worm at different speeds 80 feed operating members coaxial with said coaxial elements, and clutch means coaxial therewith. 85

73. In a mining machine, feeding mechanism including a plurality of coaxial pairs of like coaxial elements rotating on horizontal transversely extending axes, planet means 90 cooperating with the elements of each pair, and means for rotating said coaxial elements including three worms rotating on vertical axes, the central worm driving an element of each pair, means for effecting rotation of said worms including means for rotating 95 said last mentioned worm at different speeds in opposite directions, feed operating members coaxial with said coaxial elements, and clutch means coaxial therewith.

74. In a mining machine, feeding mechanism including a plurality of coaxial pairs of like coaxial elements rotating on horizontal transversely extending axes, planet means 100 cooperating with the elements of each pair, and means for rotating said coaxial elements 105 including three worms rotating on vertical axes, the central worm driving an element of each pair, means for effecting rotation of said worms including means for rotating said last mentioned worm in opposite directions or allowing it to remain stationary, 110 feed operating members coaxial with said coaxial elements, and clutch means coaxial therewith.

75. In a mining machine, feeding mechanism including a plurality of coaxial pairs of like coaxial elements rotating on horizontal transversely extending axes, planet means 115 cooperating with the elements of each pair, and means for rotating said coaxial elements including three worms rotating on vertical axes, the central worm driving an element of each pair, means for effecting rotation of said worms including means for rotating 120 said last mentioned worm at different speeds or allowing it to remain stationary, feed operating members coaxial with said coaxial elements, and clutch means coaxial therewith. 125

76. In a mining machine, feeding mecha- 130

- nism including a plurality of coaxial pairs of like coaxial elements rotating on horizontal transversely extending axes, planet means cooperating with the elements of each pair, 65
 5 and means for rotating said coaxial elements including three worms rotating on vertical axes, the central worm driving an element of each pair, means for effecting rotation of said worms including means for rotating
 10 said last mentioned worm at different speeds in opposite directions or allowing it to remain stationary, feed operating members coaxial with said coaxial elements, and clutch means coaxial therewith.
- 15 77. In a mining machine, feeding mechanism including a plurality of coaxial pairs of like coaxial elements rotating on horizontal transversely extending axes, planet means cooperating with the elements of each pair, 70
 20 and means for rotating said coaxial elements including three worms rotating on vertical axes, the central worm driving an element of each pair, means for effecting rotation of said worms including means for rotating
 25 said last mentioned worm in opposite directions and said other worms continuously in the same direction, feed operating members coaxial with said coaxial elements, and clutch means coaxial therewith.
- 30 78. In a mining machine, feeding mechanism including a plurality of coaxial pairs of like coaxial elements rotating on horizontal transversely extending axes, planet means cooperating with the elements of each pair, 75
 35 and means for rotating said coaxial elements including three worms rotating on vertical axes, the central worm driving an element of each pair, means for effecting rotation of said worms including means for rotating
 40 said last mentioned worm at different speeds and said other worms continuously in the same direction, feed operating members coaxial with said coaxial elements, and clutch means coaxial therewith.
- 45 79. In a mining machine, feeding mechanism including a plurality of coaxial pairs of like coaxial elements rotating on horizontal transversely extending axes, planet means cooperating with the elements of each pair, 80
 50 and means for rotating said coaxial elements including three worms rotating on vertical axes, the central worm driving an element of each pair, means for effecting rotation of said worms including means for rotating
 55 said last mentioned worm at different speeds in opposite directions and said other worms continuously in the same direction, feed operating members coaxial with said coaxial elements, and clutch means coaxial therewith.

- cooperating with said elements, and means for effecting rotation of one of said driving elements in opposite directions and at different speeds.
85. In a mining machine, a motor, and feeding mechanism driven by said motor including coaxial driving elements rotating on horizontal transversely extending axes, plan-

et means cooperating with said elements, and means for effecting rotation of the central driving element in opposite directions.

86. In a mining machine, a motor, and feeding mechanism driven by said motor including coaxial driving elements rotating on horizontal transversely extending axes, planet means cooperating with said elements, and means for effecting rotation of the central driving element at different speeds and in opposite directions.

87. In a mining machine, a motor, and feeding mechanism driven by said motor including coaxial driving elements rotating on horizontal transversely extending axes, planet means cooperating with said elements, means for effecting rotation of the central driving element in opposite directions and at different speeds, and means for effecting rotation of the end driving elements at a constant speed in the same direction.

88. In a mining machine, a motor, and feeding mechanism driven by said motor adapted to cooperate with flexible feeding means and including coaxial driving elements and a plurality of planet mechanisms operatively connected to said driving ele-

ments, and means for effecting rotation of one of said driving elements at different speeds and in opposite directions.

30

89. In a mining machine, a motor, and feeding mechanism driven by said motor adapted to cooperate with flexible feeding means and including three coaxial driving elements, a plurality of planetary mechanisms operatively connected to said driving elements, and means for effecting rotation of two of said driving elements in the same direction and rotation of the other driving element in a reverse direction.

35

90. In a mining machine, a motor, and feeding mechanism driven by said motor adapted to cooperate with flexible feeding means and including three coaxial driving elements, a plurality of planetary mechanisms operatively connected to said driving elements, and means for effecting rotation of two of said driving elements in the same direction and rotation of the other driving elements in a reverse direction and at a different speed.

40

In testimony whereof I affix my signature.

CHARLES F. OSGOOD.
